UNITED STATES PATENT OFFICE

JOSEPH S. BELT, OF AMARILLO, TEXAS

BATH APPARATUS

Application filed December 8, 1930. Serial No. 500,950.

The present invention relates to bath apparatus, and has more particular reference to an improved apparatus for supplying carbonated water to bath tubs or the like for 5 bathing purposes.

The present invention has particular reference to improvements in the type of apparatus set forth in my copending application for patent upon bath apparatus, Ser. 10 No. 493,211, filed November 3, 1930.

The primary object of the present invention is to generally simplify and improve prior apparatus of the above type, whereby the same may meet with all of the requirements for a successful commercial use.

Other objects and advantages will become apparent from the following description when considered in connection with the accompanying drawing, in which:

20 The figure is a diagrammatic elevation of a bath apparatus embodying the present invention.

Referring in detail to the drawing, 5 indicates a conventional type of automatic carbonator such as is commonly employed in apparatus for carbonating beverages, and which has an inlet pipe 6 for the water to be carbonated and an inlet pipe 7 for the gas by which such water is carbonated. The 25 water supply pipe 6 is preferably provided with a globe valve 8, and may be connected to a city water main as a source of water supply. Connected with the gas inlet pipe 7 by a supply line 7a is the outlet of an ordinary tank or flask 9 charged with liquid carbon dioxide under high pressure. The line 7a has a control valve 10, while a pressure regulator and gage 11 is connected in the line 7a adjacent the flask 9. Leading from the carbonator 5 is an outlet pipe 13 for the carbonated water.

The carbonator 5 has the usual electric motor —M— operatively connected to a pump —P— by which water is forced under pressure into the tank of the carbonator. Arranged in the tank of the carbonator is the usual float —F— which operates a switch —S— to control the operation of motor —M— and pump —P—. When the float —F— lowers, the motor circuit will be closed

in the usual way to cause pump —P— to force water into the tank of the carbonator for commingling with the incoming gas and being thoroughly carbonated. When the carbonated water in the tank of the carbonator 55 rises above a predetermined level therein, the float —F— operates the switch —S— to open the motor circuit and thereby throw the motor and pump out of operation.

Arranged near the carbonator 5 is a storage tank 14 into the top of which the carbonated water outlet pipe 13 discharges. Interposed in the pipe 13 is a pump —P'— operated by an electric motor —M'— whose operation is also controlled by the switch 60 —S—. The motor —M'— is thrown into and out of operation by the float switch —S— simultaneously with the motor —M—. The pump —P'— is used to force the carbonated water under pressure into the storage tank 70 14, and it is of the non-positive type through which water may flow from inlet to outlet when not in operation. A pipe 15 provides communication between the top of the storage tank 14 and the top of the tank of carbonator 5, and arranged in this pipe is a check valve 15a which permits flow from the tank 14 to the carbonator but prevents flow in the reverse direction, for a purpose which will later become apparent.

The tank 14 is provided with an outlet pipe 16 which has a control valve 17 and extends from the bottom of said tank to a faucet 18 arranged to discharge into a bath tub 19 or the like. Means is provided for heating the carbonated water within the tank 14 as disclosed in my copending application hereinbefore mentioned. A thermometer 21 indicates the temperature of the carbonated water in the tank 14, while a relief valve 23 and a pressure gage 24 are provided at the top of such tank for obvious reasons. A gage 25 indicates the level of carbonated water in the tank 14.

It is impractical to so regulate the flow of gas from flask 9 to the carbonator 5 that all of the gas will be taken in solution with the water in the carbonator. Accordingly, some of the gas necessarily passes from the carbonator to the tank 14 along with the water 100

and accumulates in the top of tank 14. After tank 14 is repeatedly filled with carbonated water, the pressure of the accumulated gas therein becomes equal to the pressure in the 5 carbonator. When this occurs, the pressure in the carbonator will not force carbonated water from the carbonator into the tank 14, and the pump —P'— is therefore required for this purpose. However, the pressure in 10 tank 14 would ordinarily eventually rise beyond the power of pump —P'— and render such pump inoperative for this purpose. Accordingly, the pipe 15 is provided so that as the water rises in tank 14 the 15 gas in the top of the latter is not compressed but is displaced through said pipe 15 back into the carbonator. In this way, the pressure in the tank 14 and in the carbonator 5 is equalized so that the pump —P'— may always operate to force the carbonated water 20 into the tank 14. The check valve 15a or its equivalent is a very important part of the present apparatus because it prevents the gas from flowing through pipe 15 from the carbonator to the tank 14. Assuming that the 25 tank 14 is filled and that the pressure in such tank and in the carbonator is the same, the pressure in tank 14 will be reduced without reducing the pressure in the carbonator 30 when water is drawn off from the tank 14 through outlet pipe 16. As soon as the pressure in tank 14 becomes lower than that in the carbonator, the pressure in the carbonator will force carbonated water from said carbonator through the non-positive pump —P'— even if the latter is not operating at 35 this particular time. This results in lowering the level of the carbonated water in the carbonator 5 so that float —F— lowers and 40 closes switch —S—, thereby throwing pumps —P— and —P'— into operation for carbonating more water in carbonator 5 and forcing more carbonated water into tank 14 as it is drawn off from the latter. Should 45 tank 14 fill with carbonated water up to the level of pipe 15, the carbonated water may return to the carbonator 5 through pipe 15, and then pass back to pump —P'—. This circulation of the carbonated water will 50 permit the same to properly accumulate in the carbonator for raising the float —F— to operate switch —S— and throw the pumps —P— and —P'— out of operation at the correct time. If desired, the pipe 15 may 55 be extended into the carbonated water tank of the carbonator so as to open therein below the level of the carbonated water, as shown by dotted lines at 15'. This will prevent free flow of gas from the carbonator to the storage tank 14 through pipe 15, so that the 60 check valve 15a might be omitted.

What I claim is:

1. In a bath apparatus, the combination of 65 a carbonator having a carbonated water tank and a motor-operated pump for supplying

said tank with water to be carbonated, said carbonator further having a float-operated switch for throwing the motor of the pump out of operation when the carbonated water rises to a predetermined level in said tank 70 and for throwing said motor into operation when said carbonated water lowers to a predetermined lower level in said tank, a storage tank connected to said carbonator to receive carbonated water from the latter, a non-positive pump for forcing the carbonated water from the carbonator to the storage tank, a motor for operating said non-positive pump operatively associated with said float-operated switch so as to be thrown into and 75 out of operation simultaneously with the motor of said water supply pump, and a gas bypass connection between the top of said storage tank and the top of the carbonator tank 80 having a check valve therein to prevent flow therethrough from the carbonator tank to the storage tank. 85

2. In a bath apparatus, the combination of a carbonator having a carbonated water tank and a motor-operated pump for supplying 90 said tank with water to be carbonated, a storage tank connected to said carbonator to receive carbonated water from the latter, a further motor-operated pump for forcing the carbonated water from the carbonator to the storage 95 tank, a float-operated switch for simultaneously throwing both of said pumps into or out of operation, and a gas by-pass connection between the top of the storage tank and the carbonator tank. 100

In testimony whereof I affix my signature.
JOSEPH S. BELT.
